[57] CLAIM

The ornamental design for a chaise lounge, as shown and described:

DESCRIPTION

FIG. 1 is a side elevational view of a chaise lounge embodying my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a perspective view thereof.

The characteristic feature of my design resides in the side frame and the continuous interconnecting brace at the rear, all as best shown in FIGS. 1 and 3.

FIG 1

*FIG 2**FIG 3*

FIG. 4

FIG 5

FIG. 6.
